J. TUOMEY
SCREENING DEVICE
Filed April 13, 1923

INVENTOR.
John Tuomey
BY C. P. Geppel
ATTORNEY

UNITED STATES PATENT OFFICE.

JOHN TUOMEY, OF NEW YORK, N. Y.

SCREENING DEVICE.

Application filed April 13, 1923. Serial No. 631,870.

To all whom it may concern:

Be it known that I, JOHN TUOMEY, a citizen of the United States, and a resident of the city of New York, borough of Manhattan, county and State of New York, have invented certain new and useful Improvements in Screening Devices, of which the following is a specification.

This invention relates to an improved screening device for pumps and the like, and more particularly to devices of that character which are used in connection with the intake of the pump to prevent foreign matter in the liquid entering the pump casting and damaging the mechanism.

It is the primary object and purpose of my present invention to provide an improved means whereby such screens or strainers may be kept thoroughly clean and free from accumulated deposits of the foreign matter so that they will at all times function perfectly to prevent such foreign matter entering the pump while permitting of the free and substantially unimpeded flow of the liquid.

In one practical embodiment of my invention, I propose to accomplish the purpose above stated by providing two screens or straining members and alternately connecting these screens with the intake and discharge sides of a pump whereby foreign matter in the liquid will be collected by one screen while the foreign matter previously collected by the other screen is removed therefrom and carried off by the liquid flowing in the opposite direction from the discharge side of the pump.

It is a further general object of the invention to provide a device of the above character which is of simple and durable construction, not liable to get out of order and which can be manufactured at relatively small cost.

With the above and other objects in view the invention consists in the improved combination and arrangement of the several parts as will be hereinafter more fully described, illustrated in the accompanying drawing and subsequently incorporated in the subjoined claims.

In the drawing, I have illustrated a simple and practical embodiment of the invention, the view thereof being an elevation partly in section and showing the pump intake and discharge connections and the supply and final discharge connections.

Referring in detail to the drawing, I have shown in the present instance, two closed chambers 1 and 2 respectively, in each of which a screen 3 and 4 respectively, is disposed substantially centrally thereof, thus dividing the chamber into two compartments.

The liquid enters the compartments at one side of the screens 3 and 4 through the supply connection 5 which is provided with branches connected to the respective chambers and having valves 9 and 10 respectively, whereby the supply of liquid to said chambers may be controlled. The chamber compartments at the opposite sides of the screens 3 and 4 are connected to the intake side of a pump (not shown) by the connection 6 also having branches leading to the respective chambers and provided with the valves 7 and 8.

The discharge side of the pump is likewise connected with the chambers 1 and 2 on the same sides of the screens 3 and 4 as the intake connection by the branched connection 11 also provided with the control valves 12 and 13.

The liquid is finally discharged from the chambers 1 and 2 under the pressure of the pump through the connection 16 having branches connected to the same ends of the chambers as the supply connection 5 and provided with the valves 14 and 15.

In the operation of the device above described, when the valves 8, 10, 12 and 14 are closed and valves 7, 9, 13 and 15 are opened, the liquid being pumped passes from the source of supply through the connection 5 and valve 9 into the chamber 1 and through screen 3 in said chamber upon which is retained any foreign matter carried by the liquid which would be likely to cause injury to the pump mechanism. The liquid then flows from the chamber 1 past the valve 7 and through the connection 6 to the intake of the pump. From the discharge side of the pump the liquid passes through the connection 11 past valve 13 and into the chamber 2 and through the screen 4 in said chamber. The liquid in passing through this screen carries away any foreign matter which may have collected thereon and which passes off with the liquid through valve 15 and is discharged through the connection 16.

When it is desired to clean the screen 3 in chamber 1, the flow of the liquid is reversed and by opening the valves 8, 10, 12 and 14

and closing valves 7, 9, 13 and 15, the liquid being pumped then passes from supply connection 5 through valve 10 into the chamber 2 and through the screen 4 which now 5 catches any foreign matter in the liquid and prevents the same from passing to the pump. The liquid then enters the pump intake connection 6 through the open valve 8. From the discharge side of the pump liquid passes 10 through connection 11 and the open valve 12 into the screen chamber 1 and through the screen 3, carrying off the foreign matter previously collected by this screen and discharging the same through valve 14 and 15 connection 16. Thus it will be seen that the two screens can be kept thoroughly clean by simply reversing the flow of the liquid through the chambers 1 and 2 so that the 20 foreign matter may not accumulate upon the screens to such an extent that it would appreciably impede the free flow of water to or from the pump.

While, in view of the very simple character of the device above described, such construction is preferred, it is possible to accomplish the same purpose by means of other alternative structures. Thus, instead of having the screens fixed or stationary, these screens might be adjustably mounted 30 so that they could be alternately positioned in connection with the intake and discharge sides of the pump, thus alternately cleaning one screen while the other serves to prevent the passage of foreign materials into the 35 pump casing. Numerous other equivalent devices for that above particularly described may suggest themselves to one skilled in the art, whereby the purpose of my present improvements can be satisfactorily attained.

Accordingly, it is to be understood that I do not regard my invention as necessarily limited to the arrangement herein illustrated and described, but reserve the privilege of adopting all such legitimate modifications in the form, proportion and relative arrangement of the several parts as may be fairly considered within the spirit and scope 40 of the appended claims.

I claim:

1. A screening device for pumps comprising two spaced relatively fixed screens, connections between each of said screens leading to the intake and to the exhaust of the pump on one side of the screens, connections 55 for each screen leading to the supply and discharge for liquid on the opposite side of the screen from said pump connections, and means for alternately opening and closing said connections with the screens of the intake and discharge sides of the pump and the liquid supply and discharge connections 60 whereby foreign matter is collected by one screen from the liquid entering the pump while foreign matter previously collected by 65 the other screen is removed therefrom and

carried off by the liquid flowing in the opposite direction from the discharge side of the pump.

2. A screening device for pumps comprising two spaced relatively fixed screens, each connected on one side thereof with the intake and discharge sides of a pump, a supply connection and a final discharge connection with the opposite sides of said screens, and means for reversing the flow of liquid through said screens whereby foreign matter is collected by one screen from the liquid entering the pump while foreign matter previously collected by the other screen is removed therefrom and carried off by the liquid flowing in the opposite direction from the discharge side of the pump. 75

3. A screening device for pumps comprising two closed chambers each having a screen therein dividing the chamber into two compartments, pump intake and discharge connections each adapted to communicate with the corresponding compartments of said chambers at one side of the respective screens, liquid supply and final discharge connections each adapted to communicate with the chamber compartments at the opposite sides of said screens, and valves interposed in each of said connections for alternately reversing the flow of the liquid through said chambers whereby foreign matter is collected by the screen in one chamber from the liquid entering the pump while foreign matter previously collected by the screen in the other pump is removed therefrom and carried off by the liquid flowing in the opposite direction through the final discharge connection from the discharge side of the pump. 85 90 100

4. In a screening device for pumps, a chamber interposed in the pipe line between the source of liquid supply and the pump, a screen in said chamber, a connection between the pump and said chamber on one side of the screen, supply and discharge connections with said chamber at the opposite side of the screen whereby in the operation of the pump said screen prevents the entrance of solids into the pump, and connections with the source, discharge and the pump for reversing the flow of liquid from the pump through said chamber whereby the solids collecting on the screen are carried off through the discharge connection. 105 110 115

5. In a screening device for pumps, a chamber interposed in the pipe line between the source of liquid supply and the pump, a screen in said chamber, connections between the intake and discharge sides of the pump and said chamber on one side of the screen, supply and final discharge connections with said chamber at the opposite side of the screen, and means for controlling the passage of liquid to and from the pump through said chamber to thereby prevent 120 125 130

the entrance of solids into the pump and to carry off the solids collecting on the screen through the final discharge connection.

6. In a screening device for pumps, a chamber interposed in the pipe line between the source of liquid supply and the pump, a screen in said chamber, a connection between the pump and said chamber on one side of the screen, supply and discharge connections with said chamber at the opposite

side of the screen, and means for controlling the passage of liquid from the pump through said chamber to carry off the solids collecting on the screen through said discharge connection.

In testimony that I claim the foregoing as my invention, I have signed my name hereunder.

JOHN TUOMEY.
